UNITED STATES PATENT OFFICE.

EDWIN F. M. SPEIDEL, OF EDGEWOOD, RHODE ISLAND.

CHAIN.

Application filed December 12, 1925. Serial No. 74,980.

This invention relates to an improvement in the construction of chains or bracelets of the extendible type, and is an improvement on my co-pending application filed November 9, 1925, Serial Number 67,794. My present invention has for its object to provide an improved form of hinge connection between the body or box links and the sliding or connecting links, whereby these links may be readily connected to or disconnected from one another for the purpose of inserting or removing one or more of these links to vary the operating length of the bracelet, provision being made for locking the hinge members against inadvertent disconnection one from the other.

A further object of the invention is the provision of an extension portion on one of the links which is arranged to act upon the next adjacent hinge to prevent inadvertent disconnecting of the hinge elements.

With these and other objects in view, the invention consists of certain novel features of construction, as will be more fully described, and particularly pointed out in the appended claims.

In the accompanying drawings:

Figure 1 is a side elevation showing my improved bracelet connected to the opposite sides of a watch.

Figure 2 is a perspective view of the main portion of the body link with the back plate removed.

Figure 3 is a perspective view of the back plate of the body member showing the abutment for the spring and the coiled hinge elements on one end thereof.

Figure 4 is a perspective view of the connecting slide link showing the hook-shaped hinge elements which are to be connected to and disconnected from the hinge elements of the body link by being slid laterally thereover, also showing the lock loop members on the opposite end of this link which are arranged to engage the hinge members of the adjacent link to prevent an inadvertent unlocking movement of the hinge parts.

Figure 5 is a perspective view of the under side of one of the chain links, showing a portion of the body link broken away to illustrate the lock members on the slide link as withdrawn from hinge engaging position.

Figure 6 is a sectional end view through the body link and the connecting link and showing the tension spring mounted therein.

Figure 7 is a side elevation showing the

cooperating hinge elements of the body and connecting links separated.

Figure 8 is a top view of the hinge elements showing them staggered and in position to be connected.

Figures 9 and 10 are edge and top views, respectively, showing the hinge elements partly connected.

Figures 11 and 12 are edge and top views, respectively, showing the hinge elements in position to be slid laterally one over the other.

Figures 13 and 14 are edge and top views, respectively, illustrating the link members as having been slid laterally and swung up into operating position, also showing the lock lug members on the rear of the slide link as having partly passed into the space between the hinge loops to prevent lateral unlocking movement thereof.

Figures 15 and 16 are edge and top views, respectively, showing the slide link in position to present its lock loop into the spaces between the hinge loops to prevent lateral movement of the hinge loops when the slide link is in its contracted position.

Figure 17 is a plan view sectioned on line 17-17 of Figure 1, showing the lock loops on one of the slide links in position to prevent lateral disengagement of the hinge members and as being withdrawn from another of the links to permit such disengagement of the hinge members.

Figure 18 is a sectional side elevation on line 18-18 of Figure 17.

It is found in the practical construction and use of bracelets of this character, of advantage to provide means whereby the links may be readily disconnected one from the other for the purpose of adding to or removing one or more links of the bracelet to change its working length; and to accomplish this in a simple and effective way, I have formed a bracelet, the links of which have a hinge construction in which both the body link and the connecting link are provided with hinge elements shaped to be connected and disconnected from each other by being slid laterally one over the other and my present invention relates more particularly to the construction of a stop or lock for preventing such lateral sliding action particularly while the links are in their contracted or normal position, that is, in order to impart to the links a lateral sliding disconnecting movement the links must be ex-

tended in order to withdraw the lock lugs on one of the links from engagement with the hinge lugs on the next adjacent link after which the link members may be moved laterally relatively to each other for ready disengagement; and the following is a detailed description of the present embodiment of my invention and showing one construction of hinge by which these advantageous results may be accomplished:—

With reference to the drawings, 10 designates the body link which is formed more or less in box-shape comprising a body portion 11 having a broad top plate 12 to receive suitable ornamentation, the edges of the side walls 13 of this body being provided with bendable flanges 14.

The back plate 15 is recessed longitudinally on its opposite edges and is adapted to be set upon the body member, the flange 14 thereof being rolled inwardly into these recesses 16 to firmly secure the back plate in position on the body thus forming a box-shaped link member.

One edge of this back plate 15, is turned inwardly, as at 17, to provide an end abutment for the tension spring 18 and the opposite end of this back plate is provided with a pair of hinge members or fingers 19 which are offset laterally from the center thereof and which members have a space 20 between them approximately the width of one of the members.

As best illustrated in Figure 4, a connecting slide link 21 is mounted in the box link to slide endways therein, its rear wall 22 providing an abutment for the opposite end of the spring 18, the opposite end 23 of this slide link being provided with a pair of hook-shaped hinge members or fingers 24, preferably of a width substantially that of the hinge members 19 on the back plate of the body and the space between the hinge members 24 is of a width to receive the hinge members 19 on said back plate, whereby as best illustrated in Figures 10 and 12 these hinge elements may be caused to interlock or interengage with each other.

On the wall 22 of the slide link, I have shown two loop-shaped stop lugs 27, but a single lug may be employed if desired and these lugs may be spaced and shaped to fit into the spaces 28 between the hinge loops 19 and 20 when assembled to prevent a disconnecting movement of the same, as presently described.

The members 24 are of a size to fit over the coils of the hinge members 19 so that when these hinge members are in axial alignment they may slide laterally relatively to each other into the position best illustrated in Figures 14 and 17, one pair being hooked over those of the other pair and then be slid laterally one over the other, one forming a pivot on which the other swings. In the

construction of these links I preferably so form the same that the hinge loops can be engaged one with the other only when the links are set at substantially right angles to each other, as illustrated in Figures 7 and 8, 70 and after these hinge members have been slid into operating position one over the other the links are swung back into substantially longitudinal alignment or to take the curve of the arm when positioned thereon, 75 in which position the edge 26 of the connecting link enters between the side walls 13 of the box link thus positively preventing lateral disengaging movement between these links except when again swung down into 80 the above-mentioned right angle position.

It is found in practice that a purchaser in examining a bracelet often swings these links down at a sharp angle one to the other, and in order to positively prevent inadvertent 85 separation when the links are in such position, I have provided an auxiliary lock in the form of one or more lugs or loops 27 formed on the rear wall of the slide link, which lugs or loops are adapted, when the 90 slide link is in contracted position, to enter the spaces 28 between the hinge loops 24 and 19 and so positively prevent a lateral disengagement of the hinge elements while this link 21 is in its normal or contracted position where it is pressed by the coil spring 18 and when it is desired to disconnect the hinge elements, it is only necessary to slide the connecting link 21 forwardly to extended position against its spring pressure sufficient distance to withdraw the lug 27 from the hinge loops, which permits a free lateral or disconnecting movement of the links when they stand at a sharp angle to each other, as 95 illustrated in Figures 7 and 9.

In assembling the parts, it is only necessary to place the connecting slide link 21 in the box link, insert the spring 18, then apply the cover plate 15 to the box link and turn the edge flanges over to lock the same 100 together.

It is now only necessary in connecting the different link units to insert the hinge elements 24 of the connecting link between the hinge elements 19 of the box link while set at a sharp angle to each other, and then slide these hinge elements one over the other and swing the links up into their normal working position where they are locked against disengagement by the edges 26 and the lock 110 lugs 27, any any number of such links may be thus connected to form a chain of any desired length.

By my improved construction of chain the links of the different units may be 115 quickly connected and disconnected from each other for the purpose of removing a damaged link or inserting a fresh link for the purpose of adjusting the operating length of the bracelet by simply swinging 120

one link down at substantially a right angle to the other and withdrawing the lugs of the slide link from between the hinge lugs, as above described.

5 The foregoing description is directed solely towards the construction illustrated, but I desire it to be understood that I reserve the privilege of resorting to all the 10 mechanical changes to which the device is susceptible, the invention being defined and limited only by the terms of the appended 15 claims.

I claim:

1. In a chain structure, a series of link 15 units each comprising a box link and a slide link therein, the slide link of one unit being detachably connected to the box link of the next unit, and means carried by each slide link for locking its box link against detachment from the slide link of the next unit 20 when said links are in contracted position.

2. In a chain structure, a series of link 25 units each comprising a box link and a slide link therein, hinge fingers on each of said links, the hinge fingers on the slide link interlocking with those of the box link of the next unit and stops carried by each slide link for maintaining said links in interlocking relation, said stops being withdrawn 30 upon expanding movement of the links of the unit.

3. In a chain structure, a series of link 35 units each comprising a box link and a slide link therein, the slide link of one unit being laterally slidably into engagement with portions of the box of the next unit for detachably connecting it thereto, and a stop carried by each slide link for engaging said 40 unit engaging portions to prevent lateral movement when said slide link is in contracted position, said stop being withdrawn from engagement upon an extending movement of the slide link relative to its box link.

4. In a chain structure, a series of body 45 links, a connecting link slidable in the body links for extendibly connecting said body links, said body and connecting links having spaced interengaging hinge elements movable into and out of engagement with each 50 other by a relative lateral sliding movement, and a locking member carried by one of the links arranged to be inserted between the hinge elements to prevent an unlocking action thereof.

5. An extendible chain structure comprising a series of box links, a connecting link 55 slidable in each box link, interconnecting hinge elements carried at one end of each box link and the end of the next adjacent connecting link, said elements being laterally slidable one over the other, a lock member carried by the opposite end of the connecting link to engage the joint elements of the adjacent hinge to prevent lateral disengaging movement of said links. 60

6. An extendible chain structure comprising a series of box links, a connecting link 65 slidable in each box link, interconnecting hinge elements carried at one end of each box link and the end of the next adjacent connecting link, said elements being laterally slidable one over the other, and a lock member carried by the opposite end of the connecting link to engage the joint elements of the adjacent hinge to prevent lateral disengaging movement of said links, said lock member being withdrawable from locked position by an expanding movement of said links. 70

7. An extendible chain structure comprising a series of body links, a series of connecting links slidable in the body link, each link of each series having a plurality of co-operating laterally spaced apart hinge elements arranged to be connected and disconnected by sliding one over the other laterally, and a locking member on the links positioned to enter the space between the hinge elements for preventing such lateral movement when in contracted position. 75

8. An extendible chain structure comprising a series of body links, a series of connecting links slidable in the body link, each link of each series having a plurality of co-operating laterally spaced hinge elements 80 arranged to be connected and disconnected by sliding one over the other laterally, stop means inoperative to prevent the separation of the joint members when the links are arranged at a sharp angle to each other, and auxiliary stop means arranged to cooperate with the first mentioned stop to assist in preventing separation of the hinge members except when the links are moved to expanded position. 85

In testimony whereof I affix my signature.

EDWIN F. M. SPEIDEL.
